PUPPET MITT POT HOLDER

Zernie Lee Ryland, 1753 W. 43rd Place,
Los Angeles, Calif. 90062

Filed Oct. 30, 1968, Ser. No. 14,368

Term of patent 14 years

Int. Cl. D2—07

U.S. Cl. D2—365

FIG. 1 is a perspective view of a puppet mitt pot holder showing my new design from a vantage point above and at one side of a partially open front end portion thereof;

FIG. 2 is a reduced-size rear elevational view thereof; and

FIG. 3 is a front elevational view of a widely open front end portion thereof.

I claim:

The ornamental design for a puppet mitt pot holder, as shown.
